(57) **CLAIM**

The ornamental design for a tire, as shown and described.

DESCRIPTION

FIG. 1 is a perspective view of a tire showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a partially enlarged view of the portion 8 in FIG. 1; and,

FIG. 9 is a partially enlarged view of the portion 9 in FIG. 2.

The broken lines shown on the drawings depict portions of the tire that form no part of the claimed design.

1 Claim, 9 Drawing Sheets
